UNITED STATES PATENT OFFICE.

JOHN RASP, OF MCKEESPORT, PENNSYLVANIA.

COMBINED CURTAIN AND SHADE HOLDER AND ROD FOR USE THEREWITH.

Application filed February 12, 1927. Serial No. 167,763.

This invention relates to a combined curtain and shade holder and rod for use therewith.

An important object of the invention is to produce a device of this character, by means of which the holder or bracket, may be so positioned that it is completely concealed by the curtain.

A further object of the invention is to provide a device of this character of such construction that the curtain rod may be readily adjusted as to effective length, so that it may accommodate oversized curtains.

A still further object of the invention is the provision of a structure of this character in which the shade fitting may be adjusted to a desired position, so that the shade is either arranged immediately adjacent the sash of the window or is spaced therefrom, as in the ordinary construction.

These and other objects I attain by the construction shown in the accompanying drawing, wherein for the purpose of illustration is shown a preferred embodiment of my invention and wherein:—

Figure 1 is a perspective view showing a curtain bracket and the coacting end of a curtain rod therefor constructed in accordance with my invention;

Figure 2 is a side elevation of the bracket, a rod being indicated in position in one of the pairs of openings in solid lines and a second rod being indicated in dotted lines in a second set of openings, as in the process of installation therein.

Figure 3 is a section on the line 3—3 of Figure 1.

Referring now more particularly to the drawing, the numeral 10 generally designates a plate having means, whereby it may be secured to the frame of a window. This means, in the present instance, comprises a flange 11 at the upper end of the plate, adapted to seat upon the upper face of the window trim and having struck-out tangs 12 adapted to enter the trim. This flange may be slid to any desired position upon the trim and then secured against shifting movements thereon by a light blow with a hammer. The plate 10, has along its side edges, flanges 13 and 14, the flange 13 being arranged at that side of the plate, which is to be disposed toward the outer side of the window. Each flange has formed there-in a series of openings 15 of a shape deter-

mined by the shape of the rod, which is to be employed with the bracket. In the present instance, flat rods, generally designated at 16, are employed, and the openings 15 are in the form of vertically elongated slots. The lower edges 16' of the slots 15 of the flange 13 are vertically spaced from the upper edges 17 of the slots 15 of the flange 14 a distance equal to the vertical depth of the rod employed, each of the openings 15 having a slightly greater aggregate depth than the depth of the rod. Between the openings 15 and the edges of the flanges 13 and 14, slots 18 are formed, permitting insertion of the rod 16 thereto. The slots 18 of the flanges 13 communicate with the openings 15 thereof above the lower ends of these openings and the peak of the metallic lug 19 thus produced at the junction of the lower wall of the slot with the opening 15 is spaced from the upper edges of the openings a distance equal to the depth of the rod 16. For the sake of uniformity in appearance, the slots 18 of the flanges 14 are preferably connected with the openings 15 thereof in a like manner.

The rod 16, which is employed, is preferably formed in two telescopically engaged sections, as illustrated, and has the free end of each section reverted in spaced relation thereto, as indicated at 20. These reverted ends can be made of desired length and actually engage in the openings 15. When engaged therein, the rods 16 may be adjusted as to effective length, so that the desired fullness of the curtain is maintained, even though the curtain be slightly wider than is necessary for a proper fit of the window. If desired, the edges of the curtains may be passed about the revert bends 21 of the rod sections, so that a portion thereof is supported from the revert proper.

The lower end of the flange 14 extends slightly below the lower edge of the plate and is provided with an extension 22 forming a shade bracket. The entire plate is preferably formed of malleable material, so that this shade bracket may be either extended to the opposite side of the plate 10 from the flanges 13 and 14 or bent back to lie alongside of the flange 14 and extend to the same side of the plate, as this flange. It will, of course, be understood that the bracket extensions will be formed in pairs. The plate 10 should be of sufficient length to

permit the lower end of the flange 14 to align with the opening of the window frame and extend thereinto, if desired.

It will be obvious that while a particular form of rod is herein disclosed for the purpose of illustration, this rod may be of any suitable character. It will also be obvious that the construction hereinbefore set forth is capable of a certain range of change and modification without materially departing from the spirit of the invention and I accordingly do not limit myself to such specific structure except as hereinafter claimed.

I claim:—

- 15 1. A curtain bracket comprising a plate having flanges on its side edges, said flanges having coacting openings for the reception of a rod, the opening of one flange being vertically offset with relation to the coating opening of the other flange.
- 20 2. A curtain bracket comprising a plate having flanges on its side edges, said flanges having coacting openings for the reception of a rod, the opening of one flange being vertically offset with relation to the coacting opening of the other flange, the edges of the flanges having slots leading into said openings and through which the rod may be introduced to the opening.
- 25 3. A curtain bracket comprising a plate having flanges on its side edges, said flanges having coacting openings for the reception of a rod, the opening of one flange being vertically offset with relation to the coacting opening of the other flange, the edges of

the flanges having slots leading into said openings and through which the rod may be introduced to the opening, said slots communicating with the openings at points spaced above the lower ends thereof.

4. A curtain bracket comprising a plate having flanges on its side edges, said flanges having coacting openings for the reception of a rod, the opening of one flange being vertically offset with relation to the coacting opening of the other flange, one of said flanges being continued below the lower end of the plate and having a continuation forming a shade bracket.

5. A curtain bracket comprising a plate having flanges on its side edges, said flanges having coacting openings for the reception of a rod, the opening of one flange being vertically offset with relation to the coacting opening of the other flange, one of said flanges being continued below the lower end of the plate and having a continuation forming a shade bracket extending to the opposite side of the plate from said flanges.

6. A curtain bracket comprising a plate having flanges on its side edges, said flanges having coacting openings for the reception of a rod, the opening of one flange having its upper edge wall vertically spaced with relation to the corresponding wall of the other opening.

In testimony whereof I hereunto affix my signature.

JOHN RASP.
